UNITED STATES PATENT OFFICE

SONIA TYCKO, OF LOS ANGELES, CALIFORNIA

COMBINATION FLUID SIPPING AND FLOAT DEVICE

Application filed November 9, 1931. Serial No. 573,903.

My invention relates to an ingenious novel device for creating childish curiosity and interest, and whereby a child in the act of sipping the contents of a vessel, is encouraged to 5 continue sipping, the floating figure during the sipping process having the deceptive appearance of swallowing the receding contents of the vessel.

The primary object of my invention is the 10 production of a device of this character whereby the interest of the person sipping the vessel's contents may be enhanced to the extent that said person will continue to imbibe the liquid until the vessel has been drained.

15 An object is to provide a device embracing said characteristics which may be utilized as a practical sipping medium for all liquids and by all persons regardless of age.

A further object is to provide a device of 20 this character that will be of peculiar benefit, and comprise a most acceptable feeding medium for infants.

A still further object of my invention is the 25 production at a low cost of a device which is conducive to the health of children, for, in the process of sipping the contents of the vessel, a child cannot gulp the liquid, but is constrained to imbibe in small quantities.

A still further object, and equally conducive 30 to the health of children, is the production of such a device whereby the device of itself tends to interest the child to the extent that it will voluntarily sip the entire contents of the vessel, this being of particular benefit 35 to mothers who are continuously confronted with the feeding problem of their offspring, and compelled by stratagem and force to get them to take or consume the proper quantity of nourishment, such as milk, fruit juices, 40 water, etc., required.

Another object, is the production of a device embracing said characteristics, whereby the childish interest created will by reason of the child consuming the entire contents of the 45 vessel, eliminate waste, and at the same time, by maintaining that interest, discourage the child from dallying so as to further eliminate the souring or otherwise spoilage of the vessel's contents.

50 Still another object is the provision of such

a device which, in addition to the foregoing, may readily be used in social functions such as afternoon teas, bridge parties and the like, as a novelty and for the purpose of a game, the person first succeeding for instance, in 55 emptying his vessel and thereby causing the float to contact with the bottom of the vessel winning the game.

I attain these objects by the combination 60 sipping and float device illustrated in the accompanying drawing, in which:

Figure 1 is a view showing my invention positioned in a glass containing a fluid as indicated by the dotted line fluid level; Figure 2 is a section on line 2—2 of Figures 1 and 4; 65 Figure 3 is a fragmentary view partly in section showing a modification of Fig. 1 with reference to the float; Figure 4 is a view partly in section of my invention as shown in Fig. 1, and Figure 5 being another modification of 70 the float member shown in Fig. 1.

Similar numerals designate like parts throughout the several views, the numeral 1 thus indicating an ordinary drinking glass containing a fluid substance 2, wherein is inserted my combination sipping and float device and comprising the sipper 3, the lowermost extremity of which diverges into an enlarged portion 4, which, although shown as a sphere, may as readily conform to any other 75 desired shape or form, said portion 4 being open as at 5 to admit into the sipper proper, the fluid contents of the vessel drawn upwardly and therethrough by the person sipping, the uppermost extremity or top end having a 80 rolled or formed edge 6 for the protection of the lips and mouth of the person sipping, a sharp edge having a tendency to cut.

An air tight float member 7 formed to 85 represent an animal as shown in Figures 1 and 2 indicating a pig, and as modified in Figures 3 and 4, to indicate a duck and a fish respectively, is positioned on the sipper, the body of the float being hollow as at 90 and air tight, a tube 9 forming an opening through the body of said float and sealing the latter into the said body as at 10 and 11 respectively, the float engaging the sipper 95 through said tube 9 and being movably disposed thereon, the action of the receding or 100

sinking fluid in the process of sipping causing the float to move downwardly, the float figure at all times engaging the vessel's contents and having the appearance of drinking the same, the enlarged portion 4 acting as a butt to prevent the float from disengaging from the sipper when the latter is withdrawn from the glass or vertically positioned otherwise.

10 In use, the sipper is placed in the vessel as illustrated in the drawing, the float figure having its head leading downwardly into the contents of the vessel. Thus, as the contents of the vessel sink or recede by reason of the sipping process, the float figure appears to be doing the drinking. This fascinates the child, holds his interest, and he continues to imbibe to the very last drop.

Produced from materials readily obtainable in the open market, such as glass, celluloid, aluminum and wood, and peculiarly lending itself to a multiplicity of designs, finishes and color schemes to attract childish fancy, the device may readily be kept in a clean and sanitary state, thus offering the buying public a novel and practical means for accomplishing the useful results herein claimed.

While I have omitted for the sake of simplicity, illustrations showing further adaptations, it should be understood that these are possible. I am also aware that slight modifications may from time to time be made in the details of construction without departing, however, from the scope of the present invention as herein set forth, and as defined in the claims which are appended hereto. Hence, I do not limit my present invention to the exact description or construction herein disclosed, but what I do claim, is:

1. In an article of the class described, the combination of a hollow rod having no interior obstruction and having one of its ends enlarged to comprise a butt end, a float having an opening therethrough and arranged

for movable engagement on said hollow rod, said butt end holding said float against disengagement from said rod when positioned for use.

2. In an article of the class described, the combination of a float means having an opening therethrough slidably receiving a hollow rod having no interior obstruction, said hollow rod having an enlarged end forming a butt end, said butt end comprising a stop means for retaining said float on said rod when the latter is vertically positioned for sipping the contents of a vessel in which said hollow rod is placed, said float in said slidable engagement on said hollow rod automatically sliding downwardly towards said butt end of said hollow rod upon receding of the liquid contents of the vessel in which said hollow rod is positioned in the sipping process, substantially as described.

3. In an article of the class described, the combination of a hollow rod having no obstructions therein and a slidably disposed float connected thereto, said rod having one of its ends enlarged to form an abutment to retain said float in engagement with said rod when positioned in a vessel for sipping its contents, and said float being adapted to slide downwardly in engagement with said rod simultaneously with the receding contents of the vessel during the sipping thereof.

4. In an article of the class described, in combination, a rod having an unobstructed hollow middle and an enlarged portion at one of its ends, a float figure comprising a body having an opening therethrough for engaging said rod in slidable relation thereto, said float body being hollow and sealed in air-tight relation with said opening, said enlarged end of said rod comprising a stop means for said float figure, and restraining the same from disengagement from said rod upon vertically positioning said rod for use.
